Attorney

UNITED STATES PATENT OFFICE.

HENRY EDMONDS, OF BIRMINGHAM, ENGLAND.

PHOTOGRAPH FRAME.

Application filed February 27, 1922. Serial No. 539,643.

To all whom it may concern:

Be it known that I, HENRY EDMONDS, subject of the King of Great Britain, residing at Birmingham, England, have invented 5 certain new and useful Improvements in Photograph Frames, of which the following is a specification.

This invention relates to improvements in photograph and like frames and refers more 10 particularly to that type of frame comprising a suitable back-plate surrounded by detachable U-section members anchored thereto, the arrangement being such that when it is desired to remove or insert a photograph from or into the frame, one or more 15 of the detachable members is or are removed, thus allowing the said operation to take place, after which the said member or members is or are replaced in position and 20 again attached to the said back-plate.

The object of the present invention is to provide an improved construction of photograph frame of this type.

According to the present invention we 25 provide a photograph frame of the type referred to having corner socket members adapted to embrace the ends of the U-shaped members, the said socket members being either separate from, attached to, or integrally with the aforesaid U-shaped members.

Further features of the invention will be hereinafter described.

Figure 1 shows a rear elevation of one form of the invention.

Figure 2 is a part cross-section taken upon the line 2—2, Figure 1.

Figure 3 is a front elevation showing two of the corner socket members and one of the U-shaped members detached.

Figure 4 is a plan and edge view of the blank from which the body of one of the corner socket members is formed.

Figure 5 is a plan and side elevation of the tail portion of one of the corner socket members.

Figure 6 is a rear view of a modified form of the invention.

Figure 7 is a similar view to Figure 6 but showing one of the end U-shaped members and its retaining clip, and also one side member detached.

Figures 8, 9 and 10 are respectively a

plan, front elevation and end elevation, of one of the bridge-members detached from the back-plate.

55

Figure 11 is a detail view on line 11—11 Figure 1.

Figure 1 shows the application of the member shown in Figures 8, 9 and 10 to the frame.

60

In carrying out this invention as shown at Figures 1—5 the frame comprises five main parts, viz., the back plate 1 and four detachable side members 2 of U-shape in cross-section which surround the said back-plate. The ends of these U-section members are mitred, as is clearly shown at Figure 3, so that when the frame is assembled they fit snugly together to form a neat joint.

65

Fitting over each corner of the frame is 70 a socket member 3 to the rear face of which a tongue piece 4 is attached.

Secured to the back-plate at suitable points adjacent each corner thereof are members 5 with which the said tongue pieces 75

engage as will be explained hereafter. These members are preferably formed from I-shaped blanks stamped out from sheet metal, these blanks being bent up so that the transverse portions of the same form 80 bridges 6 which stand away from the back-plate when the side portions of the blank rest upon the latter. To secure these members to the back plate the extremities 17 of the side portions of the blanks are bent into 85 a plane at right angles to that of the blank as seen at Figures 9 and 10 and passed through the back-plate, being then bent over upon the other side as is clearly shown at Figure 11, thus firmly securing the members in position.

To assemble the frame, the detachable side members 2 are placed in position around the glass 19 (photograph not shown), card- 90

board sheet 20, and the black plate 1 and the socket members 3 passed over the corners of the frame, so as to embrace the adjacent ends of the detachable side members, the tongue pieces of the socket members passing beneath the bridges formed by the members 95 attached to the back-plate as is clearly seen at Figure 1. All that is necessary to lock the socket members 3, and thus the detachable side members 2, is to bend the ex- 100

tremities 18 of the tongues back over the bridges, as shown at the bottom left hand corner of Figure 1.

Instead of the members secured to the back-plate being bent to form bridges they may each be provided with a slot through which the tongues pass and are then bent back as aforesaid. These members may also be formed from any other shaped blank or in any other suitable manner and may also be attached to the back-plate by any other suitable means, the above described members and method of attachment thereof being given only by way of illustration.

15 The corner socket members 3 are preferably formed from suitably shaped blanks 7, such as shown at Figure 4, stamped from sheet metal, and the tongue pieces attached thereto by soldering or by providing same 20 with laterally projecting ears 8 which are bent up at right angles and passed through slots 9 in the socket member, being then turned over on to the same thus firmly securing the tongue in position.

25 In the modified form of the invention as shown at Figures 6 and 7 the frame comprises a back-plate surrounded by four U-section members, in a similar manner to that above described. The two end members 10 are provided at their extremities with socket members 11 rigidly attached thereto and which are adapted, when the frame is assembled, to embrace the ends of the side U-section members 12, thus firmly holding the latter in position, so that they are prevented from moving either laterally or longitudinally. The end members 10 may be anchored to the back-plate in any suitable manner, but it is preferred to effect this attachment by means of U-shaped clips 13 which embrace the said end members and which are provided with tongue pieces 14 adapted to be passed beneath bridges 15 carried by members 16 mounted upon the back-plate, and then to be bent back upon themselves as shown at the left of Figure 6, thus securely attaching the aforesaid end members to the back-plate.

By the use of the construction above described only two attachment members are

required instead of four as in the first described construction as the side U-section members 12 are held in position by the said end members 10.

Instead of both the members 10 carrying the corner sockets being detachably secured to the back-plate by the tongue members as above described, only one may be so secured, the other member being permanently secured to the back-plate in any suitable manner.

Having fully described my invention, what I desire to claim and secure by Letters Patent is:—

1. A photo-frame comprising a back-plate, U-section members surrounding said back-plate, and means for securing the U-section members to the back-plate comprising bridge members carried by the back-plate and tongue pieces associated with said U-shaped members adapted to engage the said bridge members.

2. A photograph frame comprising a back-plate, U-section members surrounding the said back-plate, corner socket members which embrace the ends of the U-section members, tongue pieces carried by the corner socket members, bridge members carried by the back-plate and means for engaging the tongue pieces with the bridge members to retain the corner socket members in position.

3. A photograph frame comprising a back-plate, U-section members surrounding the said back-plate, detachable corner socket members formed from sheet metal blanks which embrace the ends of the U-section members, tongue pieces, ears upon the tongue pieces whereby the latter are secured to corner socket members, and bridge members carried by the back-plate beneath which the tongue pieces are passed and bent back upon themselves in order to retain the corner socket members in position.

In testimony whereof I have hereunto set my hand in presence of two subscribing witnesses.

HENRY EDMONDS.
